ALIGNMENT TOOL

Wayne M. Pierce, Milford, Conn., assignor to
United Aircraft Corporation, East Hartford,
Conn., a corporation of Delaware

Application June 30, 1944, Serial No. 542,906

4 Claims. (Cl. 77—55)

1

This invention relates to an improved method and improved means for aligning a master layout template in exact registry with photographic reproductions thereof, and has, among its objects the provision of a simple method utilizing a novel alignment device which enables even an unskilled person to quickly superimpose a master template on its photographic reproductions with each line or mark on the reproductions accurately aligned with the corresponding line or mark on the master template, thus assuring that any hole drilled through the master template will fall in the precisely correct location on the reproductions.

Another and more specific object of the invention is to provide an alignment tool comprising a member having a working face through which a drill bushing extends and having a plurality of pointed projections geometrically spaced about the axis of the bushing for marking by indentation metal sheets which are to be aligned.

A further object of the invention is generally to improve the method and means for aligning master templates and photographic reproductions thereof.

Other objects and advantages of the invention will be apparent from the specification and claims and from the drawing which illustrates what is now considered to be a preferred embodiment of the invention.

In the drawing, in which the same reference characters refer to identical parts throughout the several views,

Fig. 1 is a bottom plan view of the alignment tool.

Fig. 2 is a side view of the tool of Fig. 1, and

Figs. 3 to 8 illustrate the steps in using the alignment tool to obtain perfect registry of a master template with a photographic reproduction thereof.

Referring first to Figs. 1 and 2, 10 designates the body of the alignment tool which, as herein illustrated, comprises a plate of generally triangular shape having a flat working face 12. A hardened drill bushing 14 has a reduced diameter portion 16 press-fitted into a central aperture 15 with the shoulder formed by the reduced portion abutting the face of the plate which is remote from the working face. The larger diameter end of bushing 14 is similarly press-fitted into an aperture 20 in a handle 22, the bushing thus serving to rigidly connect the handle with the plate 10. A plurality of hardened inserts 24 are press-fitted into recesses in the working face of plate 10, each of which has a point 26 protruding from the working face thereof. These points are disposed in a geometrical arrangement about the axis of the drill hole 28 in bushing 16, and, as herein shown, are located at the apexes of an equilateral triangle the geometric center of which coincides with said axis. In other words, a circle inscribed about the axis of the bushing would

2

pass through all of the points 26, and these points would be equidistant on the periphery of the circle.

Figs. 3 and 4 represent a master layout template M comprising a sheet of metal 30 having the line 32 of a drawing thereon and a plurality of drilled holes 34 representing hole locations in the structural member represented by the drawing 32.

Figs. 5 and 6 represent a photographic reproduction R of template M in which the lines 32 and the holes 34 appear as photographic reproductions 32r and 34r.

In the use of the alignment tool a plurality of key hole locations are selected on the master template which are clear of the lines 32 thereon. As illustrated, three such locations 36, 37, and 38 have been chosen. The working face of the tool is applied at one of the locations sufficiently firmly to cause the points 26 to form impressions 40 in the surface thereof as illustrated in Fig. 4. While the tool is thus held a drill is passed through the drill hole 28 in bushing 14 and through the master template to form a key hole. This procedure is repeated until each of the key holes 36, 37, and 38 has been drilled in the master template.

Any desired number of photographic reproductions of the master template are now made. These may be made, for example, by the contact process which is well known. By this process the lines 32 and the hole locations 34 can be accurately reproduced on the sheet metal reproductions to exactly the same scale as the master template. As a result of the use of the alignment tool on the master template, as above described, the key holes 36, 37, and 38 will be photographically reproduced as 36r, 37r and 38r while the impressions 40 will be reproduced as pin points 40r. The points 40r are next prick-punched. Any errors in this operation tend to be averaged out due to the geometrical arrangement of the points.

The alignment tool is now applied to the reproduction at each of these key hole locations with its points 26 located in the prick-punched holes in the surface of the latter. While the tool is thus held the drill is passed through the drill hole 28 to drill the reproduction which now appears as shown in Fig. 6 in which it is an exact duplicate of the master template of Fig. 4 with the exception that the hole locations 34r have not been drilled.

As shown in Figs. 7 and 8 the master template M is superimposed on the reproduction R and suitable keys accurately conforming in diameter to the holes 36, 37, and 38 are passed through the corresponding holes in the master template and its reproduction. As herein shown, these keys are in the form of bolts 42. It will be noted that as a result of the above method of accu-

rately locating the key holes the lines 32 of the drawing on the master template are exactly coincident with lines 32r of the photographic reproduction. While the template and the reproduction are thus accurately and rigidly held in alignment, the locating holes 34 are drilled through the reproduction, the holes 34 in the master templates serving to accurately locate the drill during this operation.

As a result of this improved method and the improved alignment tool it will be evident that it has been made possible to quickly and easily align a master template with a reproduction thereof so that the holes drilled through the reproduced template from the master template will fall precisely in the correct locations on the reproductions.

It will also be evident that the use of the tool results in greater accuracy than would be possible if the key holes were simply drilled in the master template without the use of the tool, the master template were photographed and the photographic representations of the key holes on the reproductions were then drilled, since it is impossible to accurately locate the center of such a photographed hole due to the fact that its margin is fuzzy and frequently out-of-round. The impressions made by the pin points of the tool, however, appear clearly defined on the reproduction and the use of these impressions in conjunction with the alignment tool results in extreme accuracy.

While only one reproduction has been illustrated, it will be evident that a number of reproductions can be simultaneously drilled from a single master template with great speed and facility, while the reproductions are far more accurate than those hitherto produced by the painstaking work of a skilled person.

While the invention has been described with particular reference to a specific embodiment, it is to be understood that many changes may be made in the details of the construction shown without exceeding the scope of the following claims:

1. The steps in positioning the photographic reproduction of a master layout template in accurate alignment with said template which consists in, selecting key hole locations clear of the lines on said template, successively applying an alignment tool at said locations having a drill bushing and a plurality of pointed projections disposed about said bushing, passing a drill through said template at each location of a size accurately fitting said drill passage to form a key hole while forcing said tool against said template sufficiently firmly for said projections to make impressions in the surface thereof, photographically reproducing said template on a sheet of metal, prick-punching the photographic reproductions of said impressions at each hole location, applying said tool to said reproduction at each key hole location with its projections seated in the corresponding prick-punched holes therein, passing said drill through said bushing and through the reproduction to form a key hole and securing said master template and reproduction together in alignment by keys accurately fitting said holes.

2. The method of accurately transferring apertures in a master template to a photographic reproduction thereof which consists in, selecting key hole locations clear of the lines on said template, successively applying an alignment tool at said locations having a drill bushing and a plu-

rality of pointed projections disposed about said bushing, passing a drill through said bushing and through said master template at each location of a size accurately fitting the drill passage in said bushing while forcing said tool against said template sufficiently firmly for said projections to make impressions in the surface thereof, photographically reproducing said template on a sheet of metal, prick-punching the photographic reproductions of said impressions, applying said tool to said metal sheet at each of said locations with its projections seated in the corresponding prick-punched holes therein and while said tool is applied at each location passing said drill through the bushing in said tool and through the sheet, securing said master template and said reproduction together at each location by fastening means having a diameter accurately fitting the corresponding drill holes therein, and while they are secured together forming apertures in the reproduction corresponding to the apertures in said template.

3. The method of accurately photographically reproducing a master template having fastening locating holes therein which consists in selecting key hole locations clear of the lines on said template, successively applying an alignment tool at said locations having a drill bushing and a plurality of pointed projections disposed about said bushing, passing a drill through said bushing and through said template at each location of a size accurately fitting the drill passage in said bushing while pressing said tool against said template sufficiently firmly for said projections to make impressions in the surface thereof, photographically reproducing said template on a sheet of metal, prick-punching the photographic reproductions of said impressions, applying said alignment tool to said reproduced template at each of said locations with its projections seated in the corresponding prick-punched holes therein and passing said drill through the bushing in said tool and through the reproduced template, securing the master and reproduced templates together at each location by fastening means having a diameter accurately fitting the corresponding drill holes therein, and drilling the fastening locating holes in the reproduced template from the master template while the two are thus secured.

4. The method of positioning a plurality of photographic reproductions of a master layout template in exact alignment with said template which consists in, selecting key hole locations clear of the lines on the template, successively applying an alignment tool at said locations having a drill bushing located in the geometric center of a plurality of pointed projections, passing a drill through said bushing and through said template at each location of a size accurately fitting said drill passage while forcing said tool against said template sufficiently firmly for said projections to make impressions in the surface thereof, making photographic reproductions of said template on a plurality of metal sheets, prick-punching the photographic reproductions of said impressions at each hole location on the several sheets, applying said tool to said reproductions with its projections seated in the prick-punched holes at each hole location on each reproduction and passing said drill through said bushing and through the reproduction, and securing said master template and said reproductions together in alignment by shafts accurately fitting said drill holes.
